UNITED STATES PATENT OFFICE.

ERNST KRETSCHMANN, OF GROSS LAFFERDE, GERMANY.

MANUFACTURE OF INVISIBLE PICTURES.

SPECIFICATION forming part of Letters Patent No. 664,956, dated January 1, 1901.

Application filed June 26, 1900. Serial No. 21,618. (No specimens.)

To all whom it may concern:

Be it known that I, ERNST KRETSCHMANN, a citizen of the Kingdom of Prussia, and a resident of Gross Lafferde, Germany, (whose post-office address is Gadenstedterstrasse 256,) have invented certain new and useful Improvements in the Manufacture of Invisible Prints, of which the following is a specification.

10 This invention relates to a method of manufacturing invisible prints which may be made visible by heating or other means.

To produce color-changing prints, metal and other salts used in the manufacturing of sympathetic inks are mixed with varnish, just like any ordinary printing-ink. The haloid salts of cobalt are especially adapted for this purpose, their color being a pale rose when cold, but on being heated changing to a deep blue. Now a print effected by aid of a cobalt printing-ink will not be invisible, but its contours will appear plainly visible on the surface of the paper. To effect an absolute invisibility of a cobalt print, a paper having the color of the print has to be used and the print to be printed upon it. Thus a pale-rose paper being printed upon with cobalt ink will show only very faint traces of the print. To

make the latter absolutely invisible, the printing has to be done first with a fast white ink 30 and then with the rose cobalt ink covering the white. While cobalt salts lend themselves especially well to the production of such like prints, any other sympathetic—i. e., color-changing—substance may be used as 35 well, the color of the second (compensating) ink being chosen accordingly.

Having thus fully described the nature of my invention and how the same is to be performed, what I claim is—

40 The method of producing invisible prints that become visible after suitable treatment which consists in printing upon paper of any color first with a fast ink and then again with sympathetic ink, the second print covering 45 exactly the first one, and the color obtained by superposing the two prints being exactly the same as the color of the paper; substantially as and for the purpose described.

In testimony whereof I affix my signature 50 in presence of two witnesses.

ERNST KRETSCHMANN.

Witnesses:

JAY WHITE,
LEONORE KASCH.
